US00D956418S

(12) **United States Design Patent** (10) **Patent No.:** **US D956,418 S**
(45) **Date of Patent:** **** Jul. 5, 2022**

(54) **CASE FOR EARPHONES**

(71) Applicant: **GN AUDIO A/S**, Ballerup (DK)

(72) Inventor: **Johan Birger**, Ballerup (DK)

(73) Assignee: **GN AUDIO A/S**, Ballerup (DK)

(**) Term: **15 Years**

(21) Appl. No.: **29/726,444**

(22) Filed: **Mar. 3, 2020**

(30) **Foreign Application Priority Data**

Sep. 4, 2019 (EM) 001474126-0001

(51) **LOC (13) Cl.** **03-01**

(52) **U.S. Cl.**

USPC **D3/274**; D3/294; D13/108

(58) **Field of Classification Search**

USPC D3/272, 273, 274, 201, 205, 206, 218,

D3/269, 282, 294; D6/315; D7/391,

D7/601, 641; D13/107, 108; D14/201,

D14/223; D9/420, 423, 426, 428, 430,

D9/431, 432, 436, 499, 558, 717, 721

CPC H04R 1/1025; H02J 7/0044; Y02E 60/12;

Y01R 13/6675; B65D 85/182; B65D

73/02; A47F 8/02

See application file for complete search history.

(57) **CLAIM**

The ornamental design for a case for earphones, as shown and described.

DESCRIPTION

FIG. 1 is a perspective view of the Top Front Right Isometric Therefore.

FIG. 2 is a front view thereof.

FIG. 3 is a rear view thereof.

FIG. 4 is a left view thereof.

FIG. 5 is a right view thereof.

FIG. 6 is a top view thereof; and,

FIG. 7 is a bottom view thereof.

The features shown in broken lines depict environmental subject matter only and form no part of the claimed design.

1 Claim, 7 Drawing Sheets
